Aug 3 5. 99. 2,

For the Inventor of
Manufactured Rubber Cloth
Patented July 29, 1862.

UNITED STATES PATENT OFFICE.

LORIN BURT, OF THE UNITED STATES.

IMPROVEMENT IN THE MANUFACTURE OF FIGURED RUBBER CLOTH.

Specification forming part of Letters Patent No. 35,992, dated July 29, 1862.

To all whom it may concern:

Be it known that I, LORIN BURT, a citizen of the United States, now residing in France, have invented certain new and useful Improvements in the Application of India-Rubber in Designs upon Cloth; and I do hereby declare and ascertain my said invention as follows, referring to the accompanying drawing, which represents a vertical section of the machine cut through the center at right angles to the rollers, &c.

My invention consists in the particular arrangement and combination of the several parts of the machine, hereinafter described, enabling me to produce with a single printing or engraved roll the impression on both sides of the cloth at a single operation, and to subsequently remove all the gum not impressed upon the cloth in the figure required after the impression is made.

The annexed drawing is a vertical section cut through the center of the machine. The arrows indicate the direction the cylinders turn and the course of the cloth through the machine.

The cloth to be impressed with the design in india-rubber is rolled upon the cylinder A, from which it is drawn off and passes upward to cylinder B, against which it presses and receives therefrom a thin sheet of rubber, with which the surface of cylinder B is constantly coated by the supply of gum fed between it and cylinder C, as clearly indicated in the drawing. The cloth, with the continuous sheet of gum thus spread upon it on one side, passes between the engraved or printing cylinder D, on which the figure to be impressed on the cloth is raised in relief, and the plain cylinder E, on which is a thin layer of gum laid upon its surface at its junction with cylinder F. By this arrangement a thin coating of gum is brought upon both sides of the cloth, and is made to adhere thereto in any figure which the raised figure or pattern upon cylinder D determines. Thus at one operation the gum is made to adhere on each side of the cloth in determined designs at points exactly opposite.

The mode of forming the thin layers of gum and taking them from the cylinders is so well known that no further description thereof is needed by the practical workman. The gum only adheres to the cloth at the points where it has been submitted to pressure by the pattern raised upon cylinder D. Consequently the cylinder E takes away all the gum which has not been thus impressed upon the cloth. From thence the cloth passes up over a small roller and down around a second small or carrying-roller, after which the side of the cloth that first received the coating of gum from cylinder B is passed over the surface of cylinder H, on which there is a slight coating of rubber, to which all the superfluous rubber not impressed by the design on that side is taken off.

I is the counter-cylinder that lays the coating upon H. The opposite side of the cloth touches the cylinder G, that removes any rubber that may chance to escape from cylinder E. The cloth then passes around another small roller, and thence to K, where it is again rolled up with the design imprinted; as above described, thereon.

The cylinders are all driven by gearing on the journals of the cylinders outside the frame, the intermediate gear, L, by which they are moved, being connected with the driving power.

All the cylinders are heated, as usual, in the manufacture of caoutchouc so as to keep the gum in a plastic state.

Having thus fully described my invention, what I claim therein as new, and for which I desire to secure Letters Patent, is—

1. Impressing patterns in caoutchouc upon both sides of cloth substantially in the manner and for the purposes set forth.
2. Removing the superfluous gum from the cloth by means of rollers, or their equivalent, as and for the purpose described.

LORIN BURT.

Witnesses—

HENRY W. SPENCER,
GEO. HUTTON.
